UNITED STATES PATENT OFFICE.

HARRY W. BUNDY, OF DETROIT, MICHIGAN.

TUBING.

Application filed March 7, 1921. Serial No. 450,499.

to all whom it may concern:

Be it known that I, HARRY W. BUNDY, a citizen of the United States, residing at Detroit, in the county of Wayne and State of Michigan, have invented certain new and useful Improvements in Tubing, of which the following is a specification.

This invention relates to tubing and rings of tubing, and has for its object a form of 10 open seam tubing which can be manufactured very economically and which may have a variety of uses. This tubing may be manufactured in coils and may be cut up in sections to form rings when the ends are 15 welded together, as will more fully appear.

In the drawings,—

Figs. 1, 2, 3, 4 and 5 are views of the rolls showing half a coil of the stock in connection with each set of rolls as the work 20 proceeds from the first operation to the final operation.

Fig. 6 is an elevation showing a completed ring of the tubing.

Fig. 7 is an end elevation of one set of 25 rolls showing the guide which causes the stock to coil.

Fig. 1 illustrates a pair of rolls by which a plain strip of metal stock is first formed by giving it an obtuse angle at the center 30 and also by turning up the edges slightly. In the next operation shown in Fig. 2 the rolls bend the tube up the sides of the tube more and also curl in the edges slightly. In the third operation shown in Fig. 3 the rolls 35 bend up the side walls still more and curl in the rolled-over edge portions even more. In the next to the last operation shown in Fig. 4 the side walls of the tube are bent into substantially U shape and the turned-over 40 edges are folded over more sharply into beads. In the final operation the finishing rolls press the parts together as shown in Fig. 5 to complete the cross section.

It will be noticed that the diameter of the 45 coil is progressively smaller from the first coil to the last. This is accomplished by providing guides α in front of each set of rolls. These guides guide the tubing to the rolls at an angle to the ordinary path of 50 travel of the strip to the rolls, that is, at an angle to a line perpendicular to the center line through the two axes of the rolls. The greater this angle to such perpendicular line the smaller will the coil become. In 55 short, the idea is to progressively form up the cross section and coincidentally reduce the

diameter of the coil. In this manner the tubing may be formed up into the proper cross section and at the same time curved longitudinally without in any way wrinkling or deforming the product.

I am describing the way this tubing is made not for the purpose of claiming the process or describing the details of the machine. The machine might be an automatic 65 machine in which the tubing passes from one set of rolls to the other in a continuous unbroken line. On the other hand, it is possible to make the tubing by using separate sets of rolls and passing separate pieces of 70 stock through each set of rolls separately until the coil is reduced to the final diameter and the cross section is formed up into the final shape. I am simply explaining in a broad way the manufacture of this tubing 75 so that the product that I am about to claim can be reproduced by any one having only the common skill of his calling as a tube maker.

It will be obvious the open seam tubing of 80 this character has a variety of uses; for instance, it can be used in the straight lengths to form part of a bannister or balustrade, or for that matter, anywhere where a hand rail is necessary. The coil of the open seam tubing can be cut in suitable lengths and the ends 85 welded together to form a ring, as shown in Fig. 6. The welding of the ends of the open seam tubing together has a very useful function in strengthening the tubing for 90 even with tubing made out of the material of the lightest gauge after the ends have been welded together the seam cannot open up without completely distorting the material, for obviously the entire circumference 95 of the ring has to be distorted to permit the seam edges to spread. Rings of this character can be used for a variety of purposes; for instance, they may be used for hoops, 100 rims, and in any place where a circular tubular member is desired.

Throughout the specification and some of the claims I have referred to the tubing as "open seam tubing" which it is primarily. However, I wish it understood that if any 105 one manufactures tubing that originally has this open seam and chooses to close the seam by the addition of solder or other material or by welding, for instance, he still comes within the purview of my invention. Such 110 one has availed himself primarily of the open seam tubing to which has been added

simply an obvious improvement, making the tubing possibly better adapted for some uses.

What I claim is:

- 5 1. A ring, comprising a longitudinally and cross-sectionally drawn coil segment of tube with a seam formed of abutting turned in edges and with the ends of the coil segment secured together in end to end registry.
- 10 2. A tube, comprising a hollow body of circular cross-section with an outwardly

projecting seam formed by turning the metal of the edges outwardly from the circular body and returning the same to form beads which are pressed together to abut. 15

3. A ring comprising a smoothly fashioned coil segment of tube having a longitudinally running seam with abutting portions the two ends of the segment being united by a closed-butt joint. 20

In testimony whereof I affix my signature.

HARRY W. BUNDY.
